UNITED STATES PATENT OFFICE.

CHARLES JOSEPH RHODES, OF WAKEFIELD, ENGLAND.

PRESS FOR DRAWING SHEET METAL.

Application filed June 24, 1927, Serial No. 201,185, and in Great Britain February 12, 1927.

This invention relates to presses for drawing sheet metal.

In drawing sheet-metal ware, such as vessels or receptacles of considerable depth, it has been proposed to effect the drawing in a plurality of stages, usually two, for which operations two pressure rings have been employed one disposed within the other, said rings being controlled by cam or other suitably operated mechanism, suitable provision being made whereby the said rings are resiliently supported in order to compensate for differences in the thickness of the metal which may be initially present or such as may be produced during the drawing operation.

The present invention has for its object certain improvements whereby not only may the construction of the press be simplified but bodies of considerable depth may be drawn in one operation.

According to the present invention provision is made whereby the forming block or plug of the lower die, which has hitherto been stationary during the drawing operation, has imparted to it motion towards the upper die.

In order that the invention may be better understood, drawings are appended in which:—

Fig. 1 is a front view of a press embodying the present invention,

Fig. 2 is a section on line 2—2 of Fig. 1, and

Fig. 3 is a section on line 3—3 of Fig. 2.

Referring to the accompanying drawings in which only such parts are identified as are necessary for the proper understanding of the invention, 1 indicates the frame of the press and 2 the table to which is secured a plate 3 carrying the lower die 4.

5 indicates a pressure or draw ring disposed within the die 4 and supported by pins 6 passing through the table and resting upon a second table 7 disposed beneath the table 2. The table 7 is perforated for the free passage

45 of a tubular rod 8, which rod at its lower end passes through a bracket 9 comprising an upper member having upon its under surface and at each end a downwardly projecting lug 10. 11 indicates a nut whereby the bracket 9 is held against downward movement upon the tubular rod 8.

12 indicates a rubber buffer through which the tubular rod 8 passes, said buffer being interposed between the under surface of table 55 7 and the upper surface of bracket 9. The nut 11 also permits the initial adjustment of

the degree of compression upon the buffer 12.

Passing freely through the tubular rod 8 and through the base of the die is a rod 13, the upper end of which is screw-threaded and is attached to the forming block 14 of the lower die.

The rod 13 at its lower end is provided with a head 15 to which are connected the inner ends of levers 16 pivotally supported by the lugs 10 of bracket 9. The outer ends of the levers are pivotally connected to the collars 16^a on the lower ends of vertically disposed rods 17 pivotally supported at their upper ends in lugs 18 upon the underside of the table 7. The rods 17 are screw-threaded at their lower ends where they support the collars 16^a, said collars being adjustably secured to the said rods by nuts 19.

20 indicates the ram of the machine and 21 the upper die.

The operation of the machine is as follows:—As the ram descends and the upper die 21 causes the draw-ring 5 to be depressed the table 7 will be depressed compressing the buffer 12, the bracket 9 remaining stationary. The downward movement of the table 7 causes the rods 17 to operate the levers 16, which acting upon the rod 13 cause the same to move upwards whereby the plug 14 is also moved upwards.

The movement of the plug in the manner described relieves the buffer 12 of excessive compression under which it would, during the later stages of the drawing operation, oppose a substantially solid resistance to the movement of the upper die causing the metal acted upon to tear. With the present arrangement the desired resiliency of the buffer is preserved throughout the draw.

Alternatively the desired motion may be transmitted to the rod 13 by means of rack and pinion gear. For example a pinion mounted upon the lower end of the rod actuating the plug may engage other pinions on the U-shaped bracket 9 which in turn engage racks carried by the second table 7.

Claims:

1. In a press for drawing sheet metal, a movable die, a fixed die, a forming block in said fixed die, and means for moving said block toward said movable die during the drawing operation.

2. In a press for drawing sheet metal, a movable die, a fixed die, a forming block in said fixed die, a pressure ring surrounding said block, means resiliently supporting said

pressure ring, and means for moving said forming block towards said movable die during the drawing operation.

3. In a press for drawing a movable die, a fixed die, a forming block in said fixed die, a pressure ring surrounding said block, a table supporting the pressure ring, a buffer supporting said table and adapted to be compressed by said table, and means operated by said table for moving the forming block towards said movable die during the drawing operation.

4. In a press for drawing sheet metal, a movable die, a fixed die, a forming block in said fixed die, a pressure ring surrounding said block, pins supporting said pressure ring, a table supporting said pins, a resilient support for said table, a rod connected to the forming block and passing through said table, and means operable by the said table to move said forming block towards the movable die during the drawing operation.

5. In a press for drawing sheet metal, a movable die, a fixed die, a forming block in said fixed die, a pressure ring surrounding said block, pins supporting said pressure ring, a table supporting said pins, a resilient support for said table, a rod connected to the forming block and passing through said table, levers connected to said rod, supports for said levers, and means connected to said table and to said links whereby said levers are operated to move the forming block towards the movable die during the drawing operation.

6. In a press for drawing sheet metal, a movable die, a fixed die, a forming block in said fixed die, a pressure ring surrounding said block, pins supporting said pressure ring, a table supporting said pins, a resilient support for said table, a rod connected to the forming block and passing through said table, a sleeve attached at one end to the table supporting the fixed die and passing through the pressure-ring supporting table, a bracket secured to the other end of said sleeve, said rod passing through said sleeve, levers mounted upon said bracket and connected at one end to the rod, and means upon the table supporting the pressure ring connecting said table with the opposite end of said levers whereby the block is moved towards the movable die during the drawing operation.

7. In a press for drawing sheet metal, a movable die, a fixed die, a forming block in said fixed die, a pressure ring surrounding said forming block, pins supporting said pressure ring, a table supporting said pins, a

buffer supporting said table, a rod connected at one end to the forming block and passing through said table, a sleeve surrounding said rod and connected to the table for the fixed die and passing through said buffer, a bracket connected to said sleeve and supporting said buffer, levers mounted upon said bracket and connected at one end to the rod, rods pivotally connected to the pressure-ring supporting table, collars upon said rods, and pivotal connections between said rods and said levers.

8. In a press for drawing sheet metal, a movable die, a fixed die, a forming block in said fixed die, a pressure ring surrounding said forming block, pins supporting said pressure ring, a table supporting said pins, a buffer supporting said table, a rod connected at one end to the forming block and passing through said table, a sleeve surrounding said rod and connected to the table for the fixed die and passing through said buffer, a bracket connected to said sleeve supporting said buffer, levers mounted upon said bracket and connected at one end to the rod, rods pivotally connected to the pressure-ring supporting table, collars adjustably mounted upon said rods, and pivotal connections between said rods and said levers.

9. In a press, a movable die, a fixed die, a forming plug associated with said fixed die, and means operatively associated with said fixed die and plug and cooperating with said movable die to move said plug.

10. In a press, a ram-actuated die, a fixed die, and an element associated with said fixed die for movement towards said ram die.

11. In a press, a movable die, a fixed die embodying a plurality of movable elements, one of said elements being movable towards said movable die simultaneously with movement of the other element in the opposite direction.

12. In a press in combination, a movable die and a fixed die embodying a movable forming plug and means to move the plug in a direction opposite the movement of the movable die upon actuation of the latter.

13. In a press, a ram, a die associated therewith, a fixed die, a pressure ring associated therewith, a forming plug operatively associated with said pressure ring, and means whereby contact of said ram die with said pressure ring moves said plug towards said ram die.

In testimony whereof I have hereunto set my hand.

CHARLES JOSEPH RHODES.
